UNITED STATES PATENT OFFICE.

HORACE WYMAN AND ALBERT A. GORDON, OF WORCESTER, MASSACHUSETTS, ASSIGNORS TO THE CROMPTON LOOM WORKS, OF SAME PLACE.

LEVER FOR LOOMS.

SPECIFICATION forming part of Letters Patent No. 414,852, dated November 12, 1889.

Application filed August 27, 1889. Serial No. 322,071. (No model.)

To all whom it may concern:-

Be it known that we, HORACE WYMAN and ALBERT A. GORDON, both of Worcester, county of Worcester, State of Massachusetts, 5 have invented an Improvement in Levers for Looms, of which the following description, in connection with the accompanying drawings, is a specification, like letters on the drawings representing like parts.

- 10 The levers used in connection with the shedding and shuttle-box mechanisms in fancy looms are commonly made with notched ends, for the attachment thereto of cording extended to the harness-frames and to parts 15 of the shuttle-box mechanism, and these levers are made both straight and angular. These levers, commonly made of cast metal, are subjected to very considerable strain, and in rapid movement are frequently broken in 20 the line of one of the notches, the latter weakening the levers. To overcome this difficulty, we have provided the cast-metal levers with wrought-metal or steel notched ends, the said ends being firmly connected to the 25 body of the lever by casting or welding, or in other strong manner.

Our invention consists, essentially, in a loom-lever composed of a cast-metal body and notched end pieces secured thereto, as will 30 be described.

Figure 1, in side elevation, shows one form of straight lever and Fig. 2 one form of elbow-lever with our improvement added.

The lever shown in Fig. 1, it being an up-right lever, is composed, essentially, of a cast-metal body *a* and independent wrought-metal or steel ends *b b* secured firmly thereto. The lever *a* has pivoted to it a notched jack *c*. The elbow-lever shown in Fig. 2 is also com-

posed of cast-metal body, as *a*, it having connected to it the independent notched ends *b* *b*, composed of wrought or sheet metal or steel. In the formation of the said loom the independent ends *b b*, of cast malleable iron or steel, or cut or punched from sheet or wrought metal or steel, it being tougher and stronger than cast iron, may be laid into the usual mold and the cast metal be poured into the mold so as to lap over upon the ends of the said end pieces, the cast metal being made to adhere to the independent end pieces or to be welded thereto, as common in uniting two metals by casting.

In Fig. 1 the line of junction is shown at *d*; but the line of junction may be angular, and so also the end pieces may be joined to the body in other ways than that described—as, for instance, by electrically welding one part to the other.

The wrought-iron or steel end pieces cannot be broken off by strains in weaving, and a lever improved by the addition to it of the said end pieces is much more desirable than when the notches are in a cast-metal part of the lever.

We claim—

A loom-lever composed of a cast-metal body and notched end pieces of a tougher metal, substantially as described.

In testimony whereof we have signed our names to this specification in the presence of two subscribing witnesses.

HORACE WYMAN.
ALBERT A. GORDON.
